CLAIM

The ornamental design for a cordless telephone base, as shown and described.

DESCRIPTION

FIG. 1 is a top plan view of a cordless telephone base showing my new design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof; and

FIG. 7 is a top plan view of a second embodiment thereof, the remaining views of which are substantially the same as corresponding views of the FIG. 1 embodiment.

FIG. 8 is a perspective view from above of the first embodiment showing the front, top and right side of the base unit; and

FIG. 9 is a perspective view from above of the first embodiment showing the rear, top and left side.

FIG. 1.

FIG. 2.

FIG. 4

FIG. 5.

FIG. 6.

FIG. 7

FIG. 8.

FIG. 9.
